UNITED STATES PATENT OFFICE.

EDWIN W. CLARK, OF CHICAGO, ILLINOIS.

PUMP.

Specification of Letters Patent. Patented Dec. 21, 1915.

1,164,926.

Application filed January 29, 1914. Serial No. 815,121.

To all whom it may concern:

Be it known that I, EDWIN W. CLARK, a citizen of the United States, residing at Chicago, in the county of Cook and State of Illinois, have invented a certain new and useful Improvement in Pumps, of which the following is a specification.

My invention relates to pumps, and the object of the invention is to procure a practical and sure acting pump which may be lowered to the bottom of a well or cistern and operated by air or other gas under pressure conveyed to the pump itself and dispensing with pump rods or other reciprocating parts operated mechanically from the surface of the ground and leading down through the well to the pump cylinder. The ordinary deep well pumps operated by pump rods have certain inherent disadvantages, one disadvantage residing in the necessity for continually overcoming the inertia of the pump rod and connected parts which are necessarily heavy, especially where the well is of considerable depth. Heretofore no commercially successful pumps have been produced, so far as I am aware, in which all of the reciprocating parts were confined to and combined in a single pump cylinder located at the bottom of the well and operated by compressed air delivered directly to the pump cylinder.

The object of my invention is to produce a fluid actuated pump in which all of the reciprocating parts are located within a single cylinder located at the bottom of the well, the parts being so constructed and arranged as to render the operation certain, the flow continuous and uniform and to avoid the possibility of delivering air instead of water through the delivery pipe.

I accomplish my objects by the construction illustrated in the accompanying drawings in which—

Figure 1 is a central section of the pump cylinder. Fig. 1^a is a sectional view of the central portion of the pump cylinder taken on the irregular line 1^a, 1^a, Fig. 2. Fig. 1^b is a central vertical section of the lower portion of the pump cylinder. Figs. 1^a and 1^b are shown in their proper juxtaposition except that the central portion (Fig. 1^a) is taken on an irregular plane of section which renders the view more or less diagrammatic and thus facilitates an understanding of the principle of operation. Fig. 2 is a horizontal section on the line 2—2, Fig. 1^a. Fig. 3

is a horizontal section on the line 3—3, Fig. 1^a. Fig. 4 is a horizontal section on the line 4—4 Fig. 1^b. Fig. 5 is a side elevation, partly in section, of the main inlet and outlet valves.

Similar numerals refer to similar parts throughout the several views.

In the form selected to illustrate the invention the cylinder consists in general of the center casting 1, the upper and lower sections 2 and 3 respectively and the upper and lower end castings or caps 4 and 5 respectively. The center casting constitutes a valve chamber and has flanges 1^a, 1^b, projecting upward and downward from the chamber proper, said flanges being internally screw threaded to receive the threaded ends of the upper and lower cylinder sections. The upper and lower end castings are much alike in construction and by preference simply fit over the upper and lower ends of the upper and lower cylinder sections being held in position by tie rods 6. Each of the end castings or caps has an inlet chamber 7 and an outlet chamber 8. There is an inlet port and valve seat 9 in each of the upper and lower end castings interposed between the inlet chamber 7 and the inside of the cylinder. An inlet valve 10 is located at each of said ports 9 and is so arranged as to permit water to flow through the port toward the cylinder but prevent flow in the opposite direction.

While the exact form of valve is not an essential feature of the invention, it is preferably constructed as shown separately in Fig. 5 in which it will be seen that the valve has a plurality of vertical ribs 10^a leaving spaces between them for the passage of water. At one end of the ribs are lugs 10^b which are adapted to engage the valve seat when the valve is in open position and form stops for limiting the movement of the valve in this direction. At the opposite end of the valve is a threaded stud 10^c which receives a nut 10^d adapted to seat on the opposite surface of the valve seat and shut off the flow. The nut is located far enough from the lugs 10^b to permit the valve to open and close.

An outlet valve 11 is mounted in each of the end castings 4 and 5 to control the flow from the cylinder to the outlet chambers 8. The outlet valves are mounted in the valve seats 12 which form outlet ports and are preferably constructed exactly like the inlet valves 10. They are placed in such a manner however, as to permit the flow from the

cylinder but prevent flow into the cylinder. A delivery pipe 13 screws into the upper casting and leads from the upper outlet chamber to the surface of the ground or other point of delivery. A by pass 14 connects the outlet chambers 8 in the upper and lower end casting. By preference strainers 15 are placed at the admission ports 4^a and 5^a of the upper and lower end castings respectively.

The center casting 1 has an inlet chamber 16 and an outlet chamber 17 separated by a partition 18 as best shown in Fig. 2. These chambers receive air only, and the inlet chamber is supplied with compressed air through an air pipe 19 and inlet 16^a. The air, after it has performed its function escapes from the outlet chamber 17 through the air outlet 17^a to the exterior of the cylinder.

The center casting has a center boss 20 which is vertically apertured to receive the piston rod 21. In the preferred construction leakage past the piston rod is prevented by the packing nut 22. At each end of the piston rod is secured a piston or plunger which in the form shown consists of an outer disk 24, an inner disk 25 and cup leathers 26 interposed between them. These disks screw onto the ends of the piston rod, and the inner disk in each case has a hub 27 for engaging the respective strike plates 30 to thereby operate the air controlling devices which I will now describe.

The inlet chamber 16 in the center casting 1 communicates with the inside of the cylinder through the upper port and valve seat 32 and lower port and valve seat 33. The outlet chamber 17 communicates with the inside of the cylinder through the upper port and valve seat 34 and lower port and valve seat 35. A valve 36 is located within chamber 16 and is so constructed as to permit air to flow from the inlet chamber alternately to the upper and lower cylinder sections 2 and 3. A vertically ribbed stem 37 extends upward and downward from valve 36 through the ports 32 and 33, and at the end of each of the ribbed portions of the stem are stops 38 against which seat helical compression springs 39. At the outer ends said stem passes through suitable apertures in the strike plates 30 and are there provided with nuts 40 which hold the strike plates seated upon the outer end of springs 39. Extending through the outlet chamber 17 is a vertically ribbed valve stem 42 provided with valves 43 and 44 located on the outside of the ports 34 and 35 respectively. These valves 43 and 44 permit air to flow alternately from the upper and lower cylinder sections 2, 3 into the outlet chamber 17. It will be noted that the valve 36 is oppositely arranged to the valves 43 and 44, the result being that when the air

is escaping downwardly from the inlet chamber 16 it will escape downwardly to the outlet chamber 17 and vice versa. The helical compression springs 39 are interposed between the valves 43, 44 and the respective strike plates 30 and the parts are held assembled by the nuts 40 as previously described in connection with the valve in the inlet chamber.

In operation, let it be assumed that the parts are in the relative positions shown in Figs. 1, 1^a, 1^b. Under these conditions the air will pass downward from inlet chamber 16 and exert pressure upon the upper surface of the lower piston. At the same time air will escape from the space beneath the upper piston and hence the piston rod and attached parts will descend. This will force the water out from the space beneath the lower piston and cause it to flow past the lower outlet valve 11 through the by pass 14 and up through the delivery pipe 13. The pressure in the space below the lower piston will hold the lower inlet valve closed and prevent the escape of water past it. The descent of the upper piston will force the air out of the space beneath it and will at the same time permit the pressure of water in the pipe 13 to hold the upper outlet valve 11 closed to prevent the water from the by-pass from flowing anywhere except up through said pipe 13. This action will continue until the boss 27 on the upper piston reaches the upper strike plate 30 whereupon said plate will be forced downward and cause the reversal of the position of the valves 36, 43 and 44. The flow of both air and water will now be reversed and cause the rise of the piston rod and connected parts, thus permitting the space below the lower piston to fill with water and forcing the water from the space above the upper piston out through the delivery pipe 13.

From the foregoing description taken in connection with the drawings it will be evident that, as has been proved from the practical operation of the device, my pump is not only double acting and will deliver a constant stream of water up through the delivery pipe but that it is positive in its action and can by no accident (so long as the parts are intact) deliver anything but water or whatever liquid it is that surrounds the device.

If, when the pump is shut down, the pistons and attached parts should stop in intermediate position the weight of the air valves and connected parts would tend to cause said valves to descend to their respective seats and thus cause the pistons to rise as soon as the air is again turned on. Furthermore, the parts are so designed that the air valves never depart very far from their seats and hence unless valve 36 were at the mathematical center of its travel the flow of

air past it would tend to force it in one direction or the other. In my device the piston rod passes through the center of the center casting. Thus the parts are all perfectly balanced. In my pump, also, all of the air valves are inclosed within the main cylinder. This not only protects the operating parts but renders it possible to group the entire mechanism in a small compass and hence it is possible to use my device in connection with driven wells where the well casing is usually of comparatively small diameter. No priming is necessary in starting up a pump of my construction and this avoids a disadvantage found in some pumps now on the market. As a result of my construction the moving parts are all small and hence there is no need to overcome the inertia of heavy parts such as the reciprocating pump rod in use in certain present day pumps. After my pump has stopped running the weight of the entire column of water from the cylinder to the surface of the ground or other point of delivery bears upon the water valves and hence great pressure is exerted to keep said valves tightly closed. For this reason the delivery pipe tends to keep full for a long period after the pump has ceased to operate and consequently the delivery of water at the discharge end of pipe 13 commences immediately as soon as the air pressure is turned on.

Having thus described my invention, what I claim as new and desire to secure by Letters Patent, is:

1. In a fluid actuated pump, a pump cylinder, an end cap at each end of the cylinder, each end cap having non-communicating inlet and outlet chambers, an inlet valve for each of said inlet chambers, an outlet valve independent of the said inlet valve for each of said outlet chambers, said valves lying partially within and partially without the cylinder, two pistons, spaced apart and reciprocating in unison within said cylinder, a center casting in said cylinder located between the ends thereof and having an inlet and an outlet passage for the actuating fluid, an inlet controlling valve for the actuating fluid movably mounted on said center casting for permitting the actuating fluid to flow alternately into the opposite ends of the cylinder, and an outlet controlling valve for the actuating fluid mounted on said center casting and movable independently of the inlet controlling valve for permitting the actuating fluid to escape through the center casting alternately from opposite ends of the cylinder, the controlling valves being in position to be actuated by the said pistons.

2. In a fluid actuated pump, a pump cylinder, an end cap at each end of the cylinder, each end cap having non-communicating inlet and outlet chambers, an inlet valve for each of said inlet chambers, an outlet valve independent of the said inlet valve for each of said outlet chambers, said valves lying partially within and partially without the cylinder, two pistons, spaced apart and reciprocating in unison within said cylinder, a center casting in said cylinder located between the ends thereof and having an inlet and an outlet passage for the actuating fluid, an inlet controlling valve for the actuating fluid seating upon said center casting, and movable to two different positions for permitting the actuating fluid to flow alternately into the opposite ends of the cylinder, an outlet controlling valve for the actuating fluid seating upon said center casting and movable independently of the inlet controlling valve to two different positions for permitting the actuating fluid to flow alternately from the opposite ends of the cylinder out through the center casting, the controlling valves being in position to be actuated by said pistons and provided with cushioning means, a duct leading from the outlet valve at one end of the cylinder, and a by-pass leading to said duct from the outlet valve at the other end of the cylinder.

In witness whereof, I have hereunto subscribed my name in the presence of two witnesses.

EDWIN W. CLARK.
